3-AMINO-1-DIAZACYCLOALKYL-ALKYL-GUANIDINES

Robert Paul Mull, Florham Park, N.J., assignor to Ciba Corporation, New York, N.Y., a corporation of Delaware
No Drawing. Filed May 7, 1963, Ser. No. 278,750
8 Claims. (Cl. 260—268)

The present invention concerns amino-guanidines. More especially, it relates to 1-R-lower alkyl-3-amino guanidines, in which R represents N,N-(N-R₁-aza-alkylene)-imino having from four to six carbon atoms as chain members, and R₁ representing an organic radical, salts or acyl derivatives of such compounds, as well as to process for the preparation of these compounds.

An N,N-(N-R₁-aza-alkylene)-imino group may be represented by the formula:

in which each of the letters n₁ and n₂ represents one of the numbers 2, 3 and 4, with the proviso that the total of n₁+n₂ is one of the numbers 4, 5 and 6, and R₁ stands for an organic radical. A more preferred group of N,N-(N-R₁-aza-alkylene)-imino radicals may be represented by the formula:

in which each of the letters m₁ and m₂ represents one of the numbers 1 and 2, and R₁ has the previously-given meaning. Such N,N-(N-R₁-aza-alkylene)-imino radical are represented, for example, by 4-R₁-1-piperazino, 1-N,N-(3-R₁-3-aza-1,6-hexylene)imino, 1-N,N-(4-R₁-4-aza-1,7-heptylene)imino, 1-N,N-(3-R₁-3-aza-1,7-heptylene)imino and the like, in which R₁ has the previously-given meaning, and analogous radicals.

Attached to the aza-nitrogen atom of an N,N-(N-R₁-aza-alkylene)-imino group, is an organic radical R₁, which represents primarily an aliphatic radical, and especially lower alkyl having from one to seven, preferably from one to four, carbon atoms, e.g. methyl, ethyl, n-propyl, isopropyl, n-butyl, isobutyl, secondary butyl, tertiary butyl and the like, as well as n-pentyl, isopentyl, neopentyl, n-hexyl, isohexyl, n-heptyl and the like, as well as lower alkenyl, preferably allylic lower alkenyl having from three to five carbon atoms, e.g. 2-propenyl (or allyl), 2-methyl-2-propenyl (or 2-methyl-allyl), 2-butenyl (or 3-methyl-allyl) and the like, lower alkynyl, e.g. ethynyl, 1-propynyl and the like, a cycloaliphatic radical, particularly cycloalkyl having from three to seven, particularly from five to six, ring carbon atoms, e.g. cyclopropyl, cyclopentyl, cyclohexyl, cycloheptyl and the like, cycloalkenyl having from five to seven ring carbon atoms, e.g. 2-cyclopentenyl, 3-cyclohexenyl and the like, or any other suitable aliphatic radical.

The above-mentioned aliphatic, particularly lower alkyl, groups representing R₁ in the above formulae may be substituted, for example, by other aliphatic radicals, such as cycloaliphatic groups, primarily by cycloalkyl and cycloalkenyl as defined hereinabove, carboxylic aryl, particularly monocyclic or bicyclic carbocyclic aryl, e.g. phenyl, 1-naphthyl or 2-naphthyl, as well as substituted phenyl, substituted 1-naphthyl or substituted 2-naphthyl. Substituents attached to the carbocyclic radicals are, for example, lower alkyl, e.g. methyl, ethyl and the like, lower alkoxy, e.g. methoxy, ethoxy and the like, lower alkylenedioxy, e.g. methylenedioxy and the like, lower

2

alkylmercapto, e.g. methylmercapto, ethyl-mercapto and the like, nitro, amino, particularly N,N-di-substituted amino, such as N,N-di-lower alkyl-amino, e.g. N,N-dimethylamino, N,N-diethylamino and the like, halogeno, e.g. fluoro, chloro, bromo and the like, trifluoromethyl or any other suitable substituent. Groups attached to carbocyclic portions may be in any of the available positions, whereby one or more than one of the same or of different substituents may be present. Other substituents attached to an aliphatic, particularly a lower alkyl, group are heterocyclic aryl radicals, such as monocyclic aza-cyclic aryl, for example, pyridyl, e.g. 2-pyridyl, 3-pyridyl, 4-pyridyl and the like, bicyclic monocyclic azacyclic aryl, for example, quinolyl, e.g. 2-quinolyl and the like, monocyclic diazacyclic aryl, e.g. 3-pyridazinyl, 2-pyrimidyl, 4-pyrimidyl, 2-pyrazinyl and the like, monocyclic thiacyclic aryl, for example, thiienyl, e.g. 2-thienyl and the like, monocyclic oxacyclic aryl, for example, furyl, e.g. 2-furyl and the like. These heterocyclic aryl radicals may also have additional substituents, such as, for example, those attached to the above-described carbocyclic radicals.

An aliphatic radical R₁ in the above formulae, particularly a lower alkyl radical may also be substituted by functional groups, such as, for example, hydroxyl, etherified hydroxy, such as lower alkoxy, e.g. methoxy, ethoxy, n-propoxy, isopropoxy, n-butoxy, isobutoxy and the like, polyalkylenedioxy, e.g. polyethylene-dioxy, polypropylenedioxy and the like, which poly-alkylenedioxy radicals may have from two to twenty lower alkyleneoxy portions and may have a free terminal hydroxyl group or an etherified terminal hydroxyl group, such as a terminal lower alkoxy, e.g. methoxy, ethoxy and the like, group, carbocyclic aryloxy, such as monocyclic carbocyclic aryloxy, e.g. phenoxy and the like, or carbocyclic aryl-lower alkoxy, such as monocyclic carbocyclic aryl-lower alkoxy, e.g. benzyloxy, diphenylmethoxy, (4-chlorophenyl)-phenyl-methoxy and the like, or esterified hydroxyl, such as lower alkoxy-carbonyloxy, e.g. methoxy-carbonyloxy, ethoxy-carbonyloxy and the like, carbamylxy, such as carbamylxy, or N-lower alkyl-carbamylxy, e.g. N-methyl-carbamylxy and the like, N,N-di-lower alkyl-carbamylxy, e.g. N,N-dimethyl-carbamylxy and the like, or N-carbocyclic aryl-carbamylxy, particularly N-monocyclic carbocyclic aryl-carbamylxy, e.g. N-phenyl-carbamylxy and the like, or lower alkanoyloxy, e.g. acetoxy, propionyloxy and the like, or acyl groups, such as lower alkanoyl, e.g. acetyl and the like, amino, for example, unsubstituted amino, N-mono-substituted amino, for example, N-lower alkylamino, e.g. N-methylamino, N-ethylamino and the like, N-carbocyclic aryl-amino, particularly N-monocyclic carbocyclic aryl-amino, e.g. N-phenylamino and the like, N-carbocyclic aryl-lower aliphatic hydrocarbon amino, particularly N-monocyclic carbocyclic-lower alkyl-amino, such as N-phenyl-lower alkyl-amino, e.g. N-benzyl-amino, N-(2-phenylethyl)-amino and the like, or primarily N,N-disubstituted amino, such as N,N-di-lower alkyl-amino, in which lower alkyl has from one to four carbon atoms, e.g. N,N-dimethylamino, N-ethyl-N-methyl-amino, N,N-diethylamino, N,N-di-n-propylamino, N,N-di-isopropylamino and the like, N-cycloalkyl-lower alkylamino, e.g. N-cyclopentyl-N-methylamino, N-cyclohexyl-N-ethylamino and the like, N-lower alkyl-N-monocyclic carbocyclic aryl-amino, particularly N-lower alkyl-N-phenyl-lower alkylamino, e.g. N-benzyl-N-methylamino, N-methyl-N-(2-phenylethyl)-amino and the like, or N,N-alkyleneimino, N,N-oxa-alkyleneimino or N,N-aza-alkyleneimino, in which alkylene has from four to six carbon atoms as ring members, such as, for example, 1-pyrrolidino groups, e.g. 1-pyrrolidino, 2-methyl-1-pyrrolidino and the like, 1-piperidino radicals,

e.g. 1-piperidino, 2-methyl-1-piperidino, 3-methyl-1-piperidino, 4-methyl-1-piperidino, 3-hydroxy-1-piperidino, 3-acetoxy-1-piperidino, 3-hydroxymethyl-1-piperidino and the like, 1-N,N-(1,6-hexylene)-imino, 4-morpholino, or 1-piperazino radicals, particularly 4-lower alkyl-1-piperazino, e.g. 4-methyl-1-piperazino, 4-ethyl-1-piperazino, 4-(2-hydroxyethyl)-1-piperazino, 4-(2-acetoxyethyl)-1-piperazino, 4-[2-(ω -methoxy-polyethyleneoxy)-ethyl]-1-piperazino and the like, mercapto, etherified mercapto, especially lower alkyl-mercapto, e.g. methyl-mercapto, ethyl-mercapto and the like, halogeno atoms, e.g. fluoro, chloro, bromo and the like, whereby one or more than one functional group may be attached to one or more than one carbon atom of an aliphatic, particularly lower alkyl, radical.

The group R_1 in the above formulae may also represent carbocyclic aryl, primarily monocyclic carbocyclic aryl, e.g. phenyl, or bicyclic carbocyclic aryl, e.g. 1-naphthyl or 2-naphthyl, which radicals may have one or more than one of the same or different substituents attached to any of the available carbon atoms; substituents are, for example, those previously-described as being attached to a carbocyclic aryl radical. It also represents heterocyclic aryl, primarily monocyclic or bicyclic heterocyclic aryl, which have one or more than one sulfur, oxygen and/or nitrogen atom as a ring member, such as, for example, monocyclic mono-azacyclic aryl, for example, pyridyl, e.g. 2-pyridyl, 3-pyridyl, 4-pyridyl and the like, bicyclic mono-azacyclic aryl, for example, quinolyl, e.g. 2-quinolyl, 4-quinolyl and the like, monocyclic di-azacyclic aryl, for example, pyridazinyl, e.g. 3-pyridazinyl and the like, pyrimidyl, e.g. 2-pyrimidyl, 4-pyrimidyl and the like, pyrazinyl, e.g. 2-pyrazinyl and the like, pyrrol, e.g. 2-pyrrol and the like, monocyclic thiacyclic aryl, for example, thieryl, e.g. 2-thieryl and the like, or monocyclic oxacyclic aryl, for example, furyl, e.g. 2-furyl and the like, and these heterocyclic radicals substituted by substituents, such as, for example, those mentioned hereinbefore.

The lower alkyl radical, linking R with the amino-guanidino group, is represented by lower alkylene having from one to seven carbon atoms. Preferably, lower alkylene has from two to three carbon atoms, which separate the group R from the amino-guanidino group by the same number of carbon atoms; such radicals are 1,2-ethylene, 1-methyl-1,2-ethylene, 2-methyl-1,2-ethylene or 1,3-propylene. Other lower alkylene radicals are, for example, 2,3-butylene, 1,3-butylene, 1,4-butylene, 1,4-pentylene, 1,5-pentylene and the like.

The 3-amino-guanidino group may be represented by the formula:

in which each of the groups R_2 , R_3 , R_4 and R_5 stands primarily for hydrogen, but may also represent an organic substituent, such as, for example, an aliphatic group, particularly lower alkyl, e.g. methyl, ethyl, n-propyl, isopropyl and the like, as well as a carbocyclic aryl radical, particularly monocyclic carbocyclic aryl, e.g. phenyl, or phenyl substituted by one of the previously-mentioned substituents, or a carbocyclic aryl-aliphatic radical, such as monocyclic carbocyclic aryl-lower alkyl, particularly phenyl-lower alkyl, e.g. benzyl, 1-phenylethyl, 2-phenylethyl, diphenylmethyl and the like, and analogous radicals in which the phenyl portion is substituted by any of the previously-described substituents. One of the groups R_3 and R_5 may also represent an acyl radical, particularly the acyl radical of an organic carboxylic acid, such as a lower aliphatic carboxylic acid, for example, a lower alkanoic acid, e.g. acetic, propionic, pivalic acid and the like, a substituted lower alkanoic

acid, e.g. chloroacetic, dichloroacetic, hydroxyacetic, methoxy-acetic, cyclopentyl-propionic acid and the like, or a lower alkanoic acid, e.g. 3-butenoic acid and the like, a carboxylic aryl carboxylic acid, for example, a monocyclic carbocyclic aryl carboxylic acid, e.g. benzoic, hydroxybenzoic, 4-methoxybenzoic, 3,4-dimethoxybenzoic, 3,4,5-trimethoxybenzoic, 4-O-ethoxycarboxyl-syrnigic, 3,4-dichlorobenzoic, 3-N,N-dimethylamino-benzoic, 4-nitrobenzoic acid and the like, or a bicyclic carbocyclic aryl carboxylic acid, e.g. 1-naphthoic, 2-naphthoic acid and the like, or a heterocyclic aryl carboxylic acid, for example, a monocyclic heterocyclic aryl carboxylic acid, e.g. nicotinic, isonicotinic, 2-furoic acid and the like. The amino-guanidino group is more especially the group of the formula:

20 Salts of the new compounds of this invention are acid addition salts, particularly pharmaceutically acceptable, non-toxic acid addition salts, such as those with inorganic acids, e.g. hydrochloric, hydrobromic, sulfuric, phosphoric acids and the like, or with organic acids, such as organic carboxylic acids, e.g. acetic, propionic, glycolic, lactic, pyruvic, oxalic, malonic, succinic, maleic, fumaric, malic, tartaric, citric, ascorbic, maleic, hydroxymaleic, dihydroxymaleic, fumaric, benzoic, phenylacetic, 4-aminobenzoic, 4-hydroxybenzoic, anthranilic, cinnamic, mandelic, salicylic, 4-aminosalicylic, 2-phenoxybenzoic, 2-acetoxybenzoic acid and the like, or organic sulfonic acids, e.g. methane sulfonic, ethane sulfonic, 2-hydroxyethane sulfonic, p-toluene sulfonic acid and the like. Mono- or poly-salts may be formed.

25 The new compounds of this invention and the salts thereof cause in the anesthetized, normotensive dog an inhibition of the carotid occlusion reflex pressor response and antagonize the pressor responses elicited by high doses of amphetamine, and lower the arterial pressure in the unanesthetized renal or neurogenic hypertensive dog. These effects appear to be due to an inhibition of the release and/or distribution of transmitter substances from sympathetic nerve terminals. In view of the fact that the compounds of this invention block the hypertensive 30 effects of these pressor substances, they can, therefore, be used as antihypertensive agents to relieve hypertensive conditions, particularly those of neurogenic, renal or essential nature. In addition, compounds of this invention cause an increase in peripheral blood flow, and can, therefore, be used in functional peripheral vascular diseases, such as Raynaud's disease and the like. The compounds are characterized by a fast onset of the pharmacological 35 effects.

40 A preferred group of compounds of this invention are represented by the compounds of the formula:

45 in which each of the letters m_1 and m_2 have the previously-given meaning, A represents lower alkylene having from two to three carbon atoms and separating the amino-guanidino group from the $\text{N}_1\text{N}_2\text{N}-\text{R}_1$ -aza-alkylene-imino group by two to three carbon atoms, and R_1' stands for lower alkyl having preferably from one to four carbon atoms, e.g. methyl, ethyl, n-propyl, isopropyl, n-butyl and the like, and pharmaceutically acceptable, non-toxic acid addition salts thereof. Specific 50 compounds of this group are, for example,

55 3-amino-1-[2-(4-methyl-1-piperazino)-ethyl]-guanidine,
3-amino-1[3-(4-methyl-1-piperazino)-propyl]-guanidine,
70 3-amino-1-[2-(4-ethyl-1-piperazino)-ethyl]-guanidine,

5

3-amino-1-[2-(4-isopropyl-1-piperazino)-ethyl]-guanidine,
 3-amino-1-[2-[1-N,N-(3-aza-3-methyl-hexamethylene)-imino]-ethyl]-guanidine,
 3-amino-1-[2-[1-N,N-(4-aza-4-methyl-heptamethylene)-imino]ethyl]-guanidine and the like,

and the pharmaceutically acceptable, non-toxic acid addition salts thereof.

The compounds of this invention may be used in the form of compositions suitable for enteral or parenteral administration, which contain the new amino-guanidine compounds or the pharmaceutically acceptable, non-toxic acid addition salts thereof in admixture with an organic or inorganic, solid or liquid carrier. For making up such preparations there may be employed substances which do not react with the new compounds, such as water, gelatine, lactose, starches, stearic acid, magnesium stearate, stearyl alcohol, talc, tragacanth, acacia, vegetable oils, benzyl alcohols, gums, propylene glycol, polyalkylene glycols or any other known carrier used in the manufacture of such preparations. The latter may be in solid form for example, as capsules, tablets, dragees and the like, or in liquid form, for example, as solutions, suspensions, emulsions and the like. If desired, they may contain auxiliary substances, such as preserving, stabilizing, wetting, emulsifying agents and the like, salts for varying the osmotic pressure, buffers, etc. They may also contain, in combination, other useful substances.

The amino-guanidine compounds of this invention may be prepared, for example, by converting in an R-lower alkyl-amine, in which R has the above-given meaning, or a salt thereof, the amino group into an amino-guanidino group and, if desired, converting a resulting salt into the free compound, and/or, if desired, converting a resulting compound into a salt or an acyl derivative thereof.

The reagents of choice for the conversion of an amino group into an amino-guanidino group are S-lower alkyl-2-isothiocarbazides, particularly those of the formula:

in which R_3 , R_4 and R_5 have the previously-given meaning, and R_0 stands for lower alkyl, particularly methyl, as well as ethyl, n-propyl, isopropyl and the like, and acid addition salts thereof. The salts, which are employed in preference over the free base, are primarily those with mineral acids, e.g. hydrochloric, hydrobromic, hydriodic, sulfuric acid and the like. The preferred reagents are acid addition salts of S-methyl-2-isothiosemicarbazide with mineral acids, such as the hydrochloride, hydriodide, sulfate and the like. The starting material, in which the amino group is above all an unsubstituted amino group, but may also represent a substituted amino group having R_2 as the substituent, is generally used in the form of its free base.

The reaction is carried out by contacting the starting material with the reagent, preferably in the presence of an inert solvent, the choice of which depends primarily on the solubility of the reactants. Water or water-miscible organic solvents, such as lower alkanols, e.g. methanol, ethanol, propanol, isopropanol, tertiary butanol and the like, ethers, e.g. diethyleneglycol dimethyl-ether, p-dioxane, tetrahydrofuran and the like, ketones, e.g. acetone, ethyl methyl ketone and the like, lower alkanoic acids, e.g. acetic acid and the like, formamides, e.g. formamide, N,N-dimethylformamide and the like, or aqueous mixtures of such solvents represent the preferred diluents.

The reaction may be carried out at room temperature, or, if necessary, at an elevated temperature. Furthermore, it may be performed in the atmosphere of an inert gas, e.g. nitrogen, and/or in a closed vessel.

6

Analogous reagents capable of converting an amino group into an amino-guanidino group are the O-lower alkyl-2-isosemicarbazides, particularly those of the formula:

in which R_3 , R_4 , R_5 and R_6 have the previously-given meaning, or salts thereof with mineral acids. These semicarbazide derivatives are used in the same way as the above-described, corresponding 1-amino-2-isothiourea reagents; an acid addition salt of O -methyl-2-isosemcarbazide with a mineral acid, e.g. hydriodic, sulfuric acid and the like, represents a preferred reagent.

The above-described reagents are known, or, if new, may be prepared according to procedures described in the prior art and used for the manufacture of known analogs; for example, the S-lower alkyl-2-isothiosemicarbazides or O-lower alkyl-2-isosemicarbazides may be manufactured by alkylating thiosemicarbazides or semicarbazides with a lower alkyl halide, e.g. methyl or ethyl chloride, bromide or iodide and the like or with a di-lower alkyl-sulfate e.g. dimethyl sulfate, diethyl sulfate and the like.

The starting materials, i.e. the R-lower alkyl-amines, in which R has the previously-given meaning, are known or may be prepared according to known procedures. They may be obtained, for example, by treating a compound of the formula R—H, in which R has the previously-given meaning, with a halogeno-lower alkano-nitrile, in which halogeno represents, for example, chloro, bromo, and the like, or with a lower alkeno-nitrile, in which the double bond is activated by the nitrile group. In a resulting R-lower alkano-nitrile compound, the cyano group is then converted into an aminomethyl group by reduction, for example, by catalytic hydrogenation, such as, treatment with hydrogen in the presence of a catalyst containing a metal of the eighth group of the Periodic System, e.g. palladium on charcoal, Raney nickel and the like, or, preferably, by treatment with a suitable light metal hydride, for example, an aluminum hydride, e.g. lithium aluminum hydride, sodium aluminum hydride, magnesium aluminum hydride, aluminum borohydride, aluminum hydride and the like, which hydrides may be used, if necessary, in the presence of an activator, such as aluminum chloride and the like.

The compounds of the present invention may also be prepared, for example, by converting in a 1-R-lower alkyl-3-X-guanidine, in which R has the previously-given meaning, and X stands for nitro or nitroso, or a salt thereof, the group X into an amino group, and, if desired, carrying out the optional steps.

The conversion of a nitro or a nitroso group into an amino group may be carried out by per se conventional reduction methods. For example, reduction may be achieved by treatment with nascent hydrogen; the latter may be generated by contacting a suitable metal or metal compound with a hydrogen donor, for example, zinc or any other analogous metal, with acetic acid and the like, zinc acetate or any analogous metal compound with water or a moist solvent, or any other equivalent metal-hydrogen donor combination, such as, for example, an alkali metal, e.g. sodium and the like, in the presence of liquid ammonia, a lower alkanol and the like. Treatment with hydrogen in the presence of a catalyst, e.g. nickel and the like, may also be employed in the above conversion of a nitro or a nitroso group into an amino group; reduction of a nitro-guanidino group in neutral or basic medium may first lead to the formation of a nitroso-guanidino group, whereas reduction in an acidic medium yields directly the desired amino-guanidino

group. The reduction procedure may also be carried out electrolytically.

The starting materials, which are new and intended to be included within the scope of this invention, may be prepared, for example, by reacting an R-lower alkyl-amine with an S-lower alkyl-1-nitro-2-isothiourea or an S-lower alkyl-1-nitroso-2-isothiourea or an acid addition salt of such reagents; the reaction may be carried out according to the previously-described treatment of an amine with a 1-amino-S-lower alkyl-2-isothiourea. The corresponding O-lower alkyl-1-nitro-2-isoureas or O-lower alkyl-1-nitroso-2-isoureas may be substituted for the 2-isothiourea reagents.

Preferred 1-(R-lower alkyl)-3-nitro-guanidines and 1-(R-lower alkyl)-3-nitroso-guanidines used as the starting materials are, for example, those of the formulae:

and

in which R', A and the letters m_1 and m_2 have the previously given meaning, and the acid addition salts thereof. Specific starting materials of that type are, for example,

1-[2-(4-methyl-1-piperazino)-ethyl]-3-nitro-guanidine, 1-[3-(4-methyl-1-piperazino)-propyl]-3-nitro-guanidine, 1-[2-(4-ethyl-1-piperazino)-ethyl]-3-nitro-guanidine, 1-[2-(4-isopropyl-1-piperazino)-ethyl]-3-nitro-guanidine, 1-[2-(1-N,N-(3-aza-3-methyl-hexamethylene)-imino)-ethyl]-3-nitro-guanidine, 1-[2-(1-N,N-(4-aza-4-methyl-heptamethylene)-imino)-ethyl]-3-nitro-guanidine and the like, and 1-[2-(4-methyl-1-piperazino)-ethyl]-3-nitroso-guanidine, 1-[3-(4-methyl-1-piperazino)-propyl]-3-nitroso-guanidine, 1-[2-(4-ethyl-1-piperazino)-ethyl]-3-nitroso-guanidine, 1-[2-(4-isopropyl-1-piperazino)-ethyl]-3-nitroso-guanidine, 1-[2-(1-N,N-(3-aza-3-methyl-hexamethylene)-imino)-ethyl]-3-nitroso-guanidine, 1-[2-(1-N,N-(4-aza-4-methyl-heptamethylene)-imino)-ethyl]-3-nitroso-guanidine and the like, and

acid addition salts of such compounds.

The new compounds may be obtained in the form of the free compounds or as the salts thereof. A salt may be converted into the free compound in the customary way, for example, by treatment with a strong alkaline reagent, such as aqueous alkali metal hydroxide, e.g. lithium hydroxide, sodium hydroxide, potassium hydroxide and the like, or a strong quaternary ammonium anion (hydroxy ion) exchange resin and the like. A free base may be transformed into an acid addition salt thereof by reacting the latter with an appropriate inorganic or organic acid, such as one of those outlined hereinabove; such reaction may be carried out, for example, by treating a solution of the base in a suitable solvent or solvent mixture with the acid or a solution thereof and isolating the desired salt. Salts of the polybasic compounds of this invention may be obtained, in which not all of the salt-forming basic groups participate in the salt formation. Such salts may then be treated with an acid in order to form compounds, in which all or a greater number of the basic groups take part in the salt formation.

Acyl derivatives of the compound of this invention, i.e. compounds of the previous formula, in which one of the groups R_3 and R_5 represents an acyl radical as defined hereinabove, may be prepared, for example, by treating the amino-guanidine compound with the reactive derivative of a carboxylic acid, for example, with the halide,

e.g. chloride and the like, or the anhydride thereof. Such reaction may be performed in the presence of an inert solvent, for example, in a hydrocarbon, such as a lower alkane, e.g. pentane, hexane and the like or a monocyclic carbocyclic aryl hydrocarbon, e.g. benzene, toluene, xylenes and the like, or a tertiary organic base, such as a liquid pyridine compound, e.g. pyridine, collidine and the like. Acylation may also be achieved in the absence of a solvent, for example, by treating the amino-guanidine compound or a salt thereof with the acylating reagent, for example, acetic acid anhydride in a sealed tube.

The invention also comprises any modification of the general process wherein a compound obtainable as an intermediate at any stage of the process is used as starting material and the remaining step(s) of the process is (are) carried out as well as any new intermediates.

In the process of this invention such starting materials are preferably used which lead to final products mentioned in the beginning as preferred embodiments of the invention.

This is a continuation-in-part application of my application Serial No. 116,246, filed June 12, 1961, which in turn is a continuation-in-part application of my application Serial No. 76,480, filed December 19, 1960, and now abandoned.

The following examples illustrate the invention and are not to be construed as being limitations thereon. Temperatures are given in degrees centigrade.

Example 1

A mixture of 10 g. of 2-(4-methyl-1-piperazino)-ethylamine and 16.3 g. of S-methyl-2-isothiocarbazide hydriodide in 25 ml. of water is refluxed for four hours and then concentrated to dryness. The residue, recrystallized from a mixture of ethanol and diethyl ether, yields the 3-amino-1-[2-(4-methyl-1-piperazino)-ethyl]-guanidine hydriodide of the formula:

which melts at 169-172°.

The starting material may be prepared as follows: 50.4 g. of chloroacetonitrile is added dropwise to a solution of 133 g. of 4-methyl-piperazine in 100 ml. of ethanol. The mixture is refluxed, stirred for two hours and allowed to stand overnight. The solution is concentrated under reduced pressure, the residue is treated with 270 ml. of 30 percent aqueous sodium hydroxide while cooling and then extracted with ether. The ether phase is dried over solid sodium hydroxide, the solvent is removed, and the residue fractionated to yield the 4-methyl-piperazino-acetonitrile, B.P. 120-125°/12 mm. The product solidifies upon standing, M.P. 53-56°.

A solution of 50 g. of 4-methyl-piperazino-acetonitrile in 400 ml. of anhydrous ether is added to 1000 ml. of anhydrous ether containing 19 g. of lithium aluminum hydride while cooling and stirring. The reaction mixture is then refluxed for 6 hours, allowed to stand overnight and decomposed by successive addition of 17 ml. of water, 20 ml. of 30 percent aqueous sodium hydroxide and 53 ml. of water. The mixture is filtered, the filtrate is evaporated and the residue is distilled to yield the desired 2-(4-methyl-1-piperazino)-ethylamine, B.P. 90-92°/16 mm.

Example 2

A mixture of 8.55 g. of 2-(4-methyl-1-piperazino)-ethylamine and 8.32 g. of S-methyl-2-isothiocarbazide hydrochloride in 25 ml. of water is refluxed for 4½ hours. After the strong evolution of methyl-mercaptan subsides, the solution is concentrated under reduced pressure and the residual oil crystallizes on cooling. The 3-

amino-1-[2-(4-methyl-1-piperazino)-ethyl]-guanidine hydrochloride of the formula

is purified by recrystallization from a mixture of ethanol and acetonitrile, M.P. 156-159°; yield: 10.0 g.

Example 3

5.7 g. of 1-[2-(4-methyl-1-piperazino)-ethyl]-3-nitro-guanidine and 8.5 g. of zinc dust are mixed in a mortar with water to form a thick paste, which is then added to 2.5 ml. of acetic acid while stirring. The temperature is held between 0° and 10° during the mixing of the reagents and is then allowed to slowly rise to room temperature. The reaction mixture is warmed to 40° on the steam bath and held at that temperature for fifteen minutes. The solid material is filtered off, the filtrate is concentrated under reduced pressure to yield an acetate salt of 3 - amino - 1-[2-(4-methyl-1-piperazino)-ethyl]-guanidine, which is converted to the product of the procedure described in Example 2 by treatment with 6 N hydrochloric acid.

The starting material is prepared as follows: A mixture of 4.75 g. of 2-(4-methyl-1-piperazino)-ethyl-amine and 3.6 g. of S-methyl-1-nitro-2-isothiourea in 100 ml. of ethanol is refluxed for four hours. After cooling, the 1 - [2 - (4-methyl-1-piperazino)-ethyl]-3-nitro-guanidine is filtered off and recrystallized from ethanol.

In the above example, the 1-[2-(4-methyl-1-piperazino)-ethyl]-3-nitro-guanidine may be replaced by 1-[2-(4-methyl-1-piperazino)-ethyl]-3-nitroso-guanidine which upon reduction with zinc in acetic acid is converted into the 3 - amino - 1 - [2-(4-methyl-1-piperazino)-ethyl]-guanidine.

What is claimed is:

1. A member selected from the group consisting of a 1-R-lower alkyl-3-amino-guanidine, in which R is N,N-(N-R₁-aza-alkylene)-imino of the formula:

in which each of the letters m_1 and m_2 represents one of the numbers 1 and 2, and R₁ stands for lower alkyl, and in which the amino-guanidino group has the formula:

and a pharmaceutically acceptable acid addition salt thereof.

2. A compound of the formula:

in which R₁' is lower alkyl, each of the letters m_1 and m_2 stands for 1, and A is lower alkylene having from two to three carbon atoms and separating the amino-guanidino group from the ring-nitrogen atom by two to three carbon atoms.

3. A pharmaceutically acceptable acid addition salt of a compound of the formula:

in which R₁' is lower alkyl, each of the letters m_1 and m_2 stands for 1, and A is lower alkylene having from two to three carbon atoms and separating the amino-guanidino group from the ring-nitrogen atom by two to three carbon atoms.

4. 3 - amino - 1 - [2-(4-methyl-1-piperazino)-ethyl]-guanidine hydriodide.

5. 3 - amino - 1 - [2 - (4-methyl-1-piperazino)-ethyl]-guanidine hydrochloride.

6. A member selected from the group consisting of a compound having one of the formulae:

and

in which R₁' stands for lower alkyl, each of the letters m_1 and m_2 stands for one of the numbers 1 and 2, and A is lower alkylene having from two to three carbon atoms and separating the nitroguanidino and the nitroso-guanidino group from the ring-nitrogen atom by two to three carbon atoms, and an acid addition salt thereof.

7. 1 - [2 - (4 - methyl-1-piperazino)-ethyl]-3-nitro-guanidine.

8. 1 - [2 - (4 - methyl-1-piperazino)-ethyl]-3-nitroso-guanidine.
